Prepared & corrected. Samuel Kellot of San Francisco Cal.

Oct 11th 1876 L. M. Letters Patent No. 2374 Dated March 6-1866

Design for Architectural Center Flowers.

The schedule referred to in these letters Patents are making part of this paper.

To all whom it may concern:

Best known that I, Samuel Kellot of the City and County of San Francisco State of California, have originated and designed a new pattern for Center Flowers for buildings etc. of which the following is a full, clear and exact description, reference being had to the accompanying drawings making part of this specification, which is a photograph showing my pattern for design.

My Center Flower is composed of plaster of Paris, scoured, modeled, and cast in the usual manner, well known to workers in Stucco. With this exception, I prefer to cast the different portions in gelatin moulds instead of plaster, as casting in gelatin moulds imparts to the figures more beauty and bringing them out in high relief, thereby adding to the whole greater distinctness.

My said design consists of a scroll frame, with scroll and shield and bracket work placed upon it, alternated with Chimaeras, roses, and morning glories. The top of center least hollow in sections placed around the centre in the usual way.

Having thus described, my design for center flowers for buildings etc. what I claim and desire to secure by Letters Patent is the design or pattern for center flowers herein set forth.

In witness whereof I have hereunto set my hand and seal this 11th day of January A.D. 1866.

Witnesses:

A. H. Sr Jas. Mosheimer,

Sam. Kellot. E.P.
